DATA COMMUNICATIONS LINE EQUALIZER

Harold Sanders, Portola Valley, Calif., assignor to
Halcyon Communications, Inc., Palo Alto, Calif.

Filed Sept. 28, 1972, Ser. No. 293,124

Term of patent 14 years

Int. Cl. D14—02, 03

U.S. Cl. D26—5 C

Fig. 1.

Fig. 2.

Fig. 3.

Fig. 4.

FIG. 1 is a front elevational view illustrating the data communications line equalizer;

FIG. 2 is a rear elevational view of the data communications line equalizer;

FIG. 3 is an elevational view of one side of the data communications line equalizer, the other side being substantially identical thereto; and

FIG. 4 is a top plan view of the data communications line equalizer design.

I claim:

The ornamental design for a data communications line equalizer, as shown.
